FREQUENCY MODULATION

Edouard Labin, Buenos Aires, Argentina, assignor to Hartford National Bank and Trust Company, Hartford, Conn., as trustee

Application October 14, 1942, Serial No. 462,013

2 Claims. (Cl. 179—171.5)

1

The present invention relates to radio transmission of the type in which the transmitted wave is frequency modulated. More particularly, the invention is concerned with the production of the frequency modulated wave by a method of direct phase modulation.

In my prior application Serial No. 450,596 of July 11, 1942, on a "Method of producing frequency modulated waves for radio transmission," I have set forth the chief difficulties encountered in frequency modulated transmission, and have shown that the frequency modulated wave may be expressed as $u=U \sin(\Omega_0 t + \psi)$ where ψ is a term representing the integrated intelligence and is given by $2\pi k \int s(t) dt = 2\pi k A \sigma(t) dt = \beta \int s(t) dt$, $s(t) = A \sigma(t)$ being the intelligence to be introduced into the wave. I have further recalled in the aforesaid prior application that the wave $u=U \sin(\Omega_0 t + \psi)$ may be obtained by mixing a sinusoidal H. F. oscillation $w=U_0 \sin \Omega_0 t$, of the central frequency Ω_0 with an oscillating L. F. tension $v=V \cos \psi$, where the value of the angle ψ is $k \int s(t) dt$, on the assumption that it were possible to produce, from the integrated intelligence $s(t)$ such an oscillating tension $v=V \cos \psi$. In said prior application, a practical solution was found by a particular utilization of the Kerr cell.

In the prior application Serial No. 453,890, filed August 6, 1942, in the names of Edouard Labin and Manuel Julio Kobilsky, a thermionic tube is described whereby inter alia an output may be obtained which is a sinusoidal function of an electrical quantity impressed on control members provided in operative relationship with respect to an electronic beam. It likewise describes general methods for determining the shape and/or composition of secondary emission surfaces on the basis of which surfaces capable of yielding a sinusoidal output may be constructed. It is therefore deemed unnecessary to detail in the present specification the construction of the forming device or the manner of designing the forming elements thereof.

It will be sufficient therefore, for the purposes of the present invention to recall that the tubes of said prior specification of Edouard Labin and Manuel Julio Kobilsky are of the kind comprising the generation of a beam of electrons which is passed through a spatial displacement zone on which is impressed an electrical quantity acting to control the extent of the spatial displacement, the beam after leaving said spatial displacement zone passing to a forming zone the geometry and composition of which is such that the intensity of the electric current emerging therefrom is a

2

sinusoidal function of the spatial displacements of the said beam.

For the purposes of the present invention and in accordance with the hereinabove recalled theory, I use for the electrical quantity controlling the spatial displacement a varying and oscillating electrical quantity so that the output of the forming zone is a sinusoidal function of such varying and oscillating electrical quantity. To obtain an output which shall be a sinusoidal function of the sum of two angles, as in frequency modulated transmission, two such forming zones are used, one in quadrature with the other to obtain the terms in $\sin \psi$ and $\cos \psi$ and the two outputs are combined severally with sinusoidal functions of a central frequency obtained by impressing a central frequency generated in a stabilized pilot, on respective phase shifting zones in quadrature, the two combinations then being applied simultaneously to a common point of an electrical system, such as a transmitter.

For frequency modulated transmission, the varying and oscillating electrical quantity is the integrated intelligence so that the resulting wave is $u=U \sin(\Omega_0 t + \psi)$.

The fundamental advantage of employing the tube mentioned is the new possibility of obtaining in one step values of ψ as high as a number of times 2π .

30 It is, therefore, a principal object of the present invention to provide, particularly in connection with frequency modulated radio transmission, a new and improved method of generating an electrical quantity varying as a sinusoidal function of the sum of two angles, each of said angles being respectively proportional to one of two other electrical quantities.

A further object of the present invention is to provide a method for generating, for an electrical system, an electrical quantity varying as a sinusoidal function of the sum of two angles, which comprises the steps of generating a stabilized central frequency, passing the central frequency simultaneously through two separate zones of phase displacement in quadrature with each other whereby to obtain two sinusoidal oscillations of central frequency in quadrature with each other and thereby to provide factors which are sinusoidal functions in quadrature of one of said angles, generating a varying and oscillating other electrical quantity, generating two electron beams, each beam corresponding to one of said phase displacement zones, passing each beam through a respective spatial displacement zone and a forming zone the geometry and composition

of which is such as to give at its output an emerging electrical quantity which is a sinusoidal function of the spatial displacement impressed on the respective beam, one forming zone being in quadrature with the other, controlling the operation of each spatial displacement zone by impressing thereon as a control factor said varying and oscillating other electrical quantity, whereby to obtain as output factors, emerging electrical quantities which are sinusoidal functions in quadrature of the other of said angles, combining each of said emerging electrical quantities with the quadrature sinusoidal function of central frequency and applying the resulting combinations simultaneously to a common point of said electrical system.

A further object of the present invention is to provide a method for generating, for an electrical system, an electrical quantity varying as a sinusoidal function of the sum of two angles, which comprises the steps of generating a stabilized central frequency, passing the central frequency simultaneously through two separate zones of phase displacement in quadrature with each other whereby to obtain two sinusoidal oscillations of central frequency in quadrature with each other and thereby to provide factors which are sinusoidal functions in quadrature of one of said angles, generating a varying and oscillating other electrical quantity, generating two electron beams in respective generating zones while impressing on one generating zone one of said sinusoidal oscillations of central frequency and the other sinusoidal oscillation of central frequency on the other generating zone to impress on the respective beams sinusoidal variations in intensity in quadrature with each other and representative of said one angle, passing each intensity modulated beam through a respective spatial displacement zone followed by a forming zone, the geometry and composition of which is such as to impress on the output a modulation which is a sinusoidal function of the spatial displacement impressed on the respective beam during its passage through the spatial displacement zone, controlling the operation of each spatial displacement zone by impressing thereon, as a control factor, said varying and oscillating other electrical quantity, whereby to combine with the intensity modulation corresponding to the sinusoidal function of said one angle a modulation corresponding to a quadrature sinusoidal function of said other angle, and applying the two outputs of the forming zones simultaneously to a common point of said electrical system.

These and other objects and advantages of the present invention will become apparent in the course of the following detailed description in which reference is made to the accompanying drawings.

In the drawings:

Fig. 1 is a diagram illustrating the application of the invention to the generating of a frequency modulated wave.

Fig. 2 is a diagram illustrating a modified form of application.

Fig. 3 illustrates one form of apparatus suitable for the purposes of the invention.

Given the principle of obtaining the sinusoidal factors of the angle ψ by impressing on a beam of electrons spatial displacements in response to a varying and oscillating electrical quantity, causing said beam to enter a forming zone and deriving from the forming zone a sinusoidal function of said varying oscillating electrical quantity, the

desired final result, namely an electrical quantity varying as the sinusoidal function of the sum of two angles one of which corresponds to said varying and oscillating electrical quantity, and the other of which corresponds to a central frequency, may readily be obtained by connecting the operative parts in a manner which is in itself quite classical. Such assembly of the operative parts or inter-relationing of the several zones is illustrated diagrammatically in Fig. 1.

The elements PS_1 and PS_2 , labelled Phase-shifters, are adapted to give to the oscillation Ω_c originating from the stabilized pilot SP , two forms in quadrature,

$$u_1 = U_0 \sin \Omega_c t, \text{ and } u_2 = U_0 \cos \Omega_c t$$

The elements PM_1 and PM_2 , designated phase modulators, receive the intelligence $s(t)$ —if necessary already integrated—and make of it two signals in quadrature

$$v_1 = V_0 \sin \psi, \text{ and } v_2 = V_0 \cos \psi$$

The said phase modulators are constituted in accordance with the teaching of the said prior patent application of E. Labin and M. J. Kobilsky. A suitable phase modulator is shown in Fig. 3 and comprises an electron discharge tube 10 having an evacuated and hermetically sealed envelope including an indirectly heated cathode 12, a heating filament 14, an intensity control grid 16 and a beam concentrating means 18, so arranged that from said beam concentrating means 18 there issues a beam of electrons having a desired cross section. The tube also comprises beam-deflecting electrodes 20—20 arranged on the side of the beam concentrator 18 remote from the cathode.

On the side of the deflecting electrodes 20—20 remote from the cathode and in the path of the electron beam, there is provided a response forming element 22 having a secondary electron emissive surface with sinusoidal undulations. A passive collector electrode 24 is provided for collecting the secondary electrons provided by the element 22. A suitable load impedance 25 is provided in the output circuit of the collector electrode 24.

In operation the phase modulator of Fig. 3 provides an output voltage e containing the desired argument, $V \cos \psi$ or $V \sin \psi$ by reason of the movement of the electron beam under the influence of the deflecting electrodes 20—20 whereby a voltage $s(t)$ applied to these electrodes causes the beam to scan the undulated surface 55 of the element 22 and produce a secondary emissive current to the collector 24 proportional to the angle of incidence of the beam with respect to the surface of the element. Whether the argument $\cos \psi$ or $\sin \psi$ is generated is determined by the initial or resting position of the beam with respect to the undulated surface of element 22 and one or the other function is obtained by suitable selection of the resting position of the beam with respect to the position of the element.

The arrangement shown in Fig. 1 comprises two tubes of the foregoing type such tubes constituting the phase-modulators PM_1 and PM_2 and by applying the intelligence voltage $s(t)$ to the deflecting electrodes 20—20 thereof, the arguments $\cos \psi$ and $\sin \psi$ are produced.

The multiplication of each L. F. oscillation, v_1, v_2 , with the corresponding H. F. oscillation, u_1, u_2 , is carried out in two classical modulators M_1, M_2 , which have been designated “intensity modulators” to distinguish them from the phase

modulators. To add the two products thus obtained, $mu_1v_1=U \sin \Omega ct \cos \psi$, and $mu_2v_2=U \cos \Omega ct \sin \psi$, it is sufficient to apply the outputs of the intensity modulators simultaneously to a common point of an electrical system, such as a transmitter, as indicated at T in the figure.

An ordinary intensity modulation generates not only the products $U \sin \Omega ct \cos \psi$, and $U \cos \Omega ct \sin \psi$, but, at the plate of the modulating tube, there also appear currents which reproduce the two individual oscillations applied. The L. F. oscillation will not give an output voltage, because the plate circuit will be closed through a filter capable of rejecting it completely. But such a filter cannot reject the current Ωct , located right in the middle of the band which it must transmit. However, a differential modulator of the classical type can be used for the intensity modulators to eliminate the central frequency by a process of internal opposition. Should the management of such a modulator prove to be too delicate a matter, due to a working frequency Ω_c which is already high, it will be sufficient to use a method of frequency conversion and create the two modulations, in phase and in intensity, on a lower frequency Ω_c . Furthermore, it should be mentioned that the presence of a certain portion of pure central frequency beyond the modulating system, and hence up to within the aerial, does not do much damage to the reception of the useful wave, so long as such portion does not exceed a value of some tenths (in power) of the useful wave. In fact, it is known that the reception of frequency modulated waves offers a very good protection against interference signals the amplitude of which is a few times lower than that of the desired signal, wherever the frequency of the former is located with respect to that of the latter. The same may be said of any lack of symmetry between the two paths, which is translated by the persistence of a lateral band at the output, alongside the desired wave. It is thus seen that the arrangement of the system of mixture is not critical.

The multiplication of an L. F. tension $v_1=V \cos \psi$ by an H. F. voltage $u_1=U_0 \sin \Omega ct$, may, as shown in Fig. 2, be effected without the differential modulators of Fig. 1, whenever the intensity V of the L. F. voltage can be controlled independently. In the arrangement shown in Fig. 2 the outputs of the phase shifters PS_1' and PS_2' are each applied to the intensity control grid 16 of the tubes 10 constituting the phase modulators PM_1' and PM_2' to thereby intensity modulate the respective electron beams. The intelligence voltage $s(t)$ is applied to the deflecting electrodes 20-20 of each of the tubes. In this arrangement the desired multiplication is effected in each tube whereby the output voltage e of the phase modulator PM_1' comprises the desired argument $\sin \Omega ct \cos \psi$ and the output voltage of phase modulator PM_2' comprises the argument $\cos \Omega ct \sin \psi$ as indicated in Fig. 2. Let it be supposed that the phase modulator PM_1' which provides $V \cos \psi$ from $s(t)$ (or from $\psi=k \int s(t) dt$), operates without perturbations whatever may be the amplitude V, and, more particularly, even if the amplitude V varies in time with an H. F. rhythm. Then it is purposely controlled by the phase-shifted piloted frequency from PS_1' , that is to say, the control voltage is made to be of the type $V=V_0 \sin \Omega ct$, so that from the phase modulator PM_1' the output is directly the product $V_0 \sin \Omega ct \cos \psi$. The complementary phase modulation path PM_2' , which generates $\sin \psi$,

would be modulated in intensity by the phase-shifted piloted oscillation in quadrature $\cos \Omega ct$ from PS_2' . The combination, at a common point T' of the outputs of the two paths, effects the addition required to give the complete wave. In this embodiment, two differential modulators as well as two separate outputs for the two phase modulation paths are suppressed, and the necessary devices are added to control the amplitude of the L. F. oscillations in accordance with the rhythm of the H. F. oscillation. The net result of this is always a simplification of the system.

It can be shown that in order to obtain the desired resultant which shall be a sinusoidal function of the sum of the two angles Ωct and ψ , it will suffice to combine the two output points of the forming zones. This means in practice that a twin forming device with a collecting anode common to the two parts, may be used.

The undesired parts of the output which reproduce the piloted oscillations can be eliminated by opposing two voltages of appropriate amplitude taken directly from the phase shifters, since within the range of frequencies utilized, the accurate opposition of two voltages at a point remote from that of formation offers no special difficulties. Such elimination is indicated in the broken lines in Fig. 2 leading from the phase shifters PS_1' and PS_2' , to an opposition zone ZO.

Calculation based on suitable assumed values demonstrates that the parasitic phase displacement introduced by differences in the length of path of the electron beam as it moves over a configured secondary emission surface will not prove troublesome.

The only disadvantage of the intensity modulation carried out directly in the tube, is that the amplitude of the useful electrical currents cannot be more than a fraction of the mean constant part thereof, owing to the necessity for the linear control of the grid by the piloted oscillation. Hence, in order to obtain for the proper intensity for said amplitude a total emission a few times greater must be taken from the cathode of the tube. But this is still not a serious matter, if the concentration system is carefully adjusted.

I claim:

1. A method of generating an electrical quantity varying as a sinusoidal function of the sum of two angles, comprising the steps of deriving two oscillations in phase quadrature from a wave having a stable frequency, generating a varying and oscillating electrical quantity, generating two electron beams, modulating the intensity of one of said beams proportional to the amplitude of one of said oscillations, modulating the intensity of the other beam proportional to the amplitude of the other of said oscillations, deflecting each of said beams proportional to the amplitude of the varying and oscillating electrical quantity, deriving from the intensity modulated and deflected electron beams secondary emissive currents proportional to the amplitude of said oscillations and sinusoidal functions in quadrature of said varying and oscillating electrical quantity, and combining the said secondary emissive currents.

2. A method of generating an electrical quantity varying as a sinusoidal function of the sum of two angles, comprising the steps of deriving from a wave having a stable frequency two oscillations in phase quadrature, the argument of said wave constituting the first of said angles, while the second angle is proportional to a generated

varying and oscillating electrical quantity, generating two electron beams, modulating the intensity of one of said beams proportional to the amplitude of one of said oscillations, modulating the intensity of the other beam proportional to the amplitude of the other of said oscillations, deflecting each of said beams proportional to the amplitude of the varying and oscillating electrical quantity, deriving from the intensity modulated and deflected electron beams secondary emissive currents proportional to the amplitude of said oscillations and sinusoidal functions in quadrature of the second of said angles proportional to said varying and oscillating electrical quantity, combining the said secondary emission currents to produce a resulting quantity comprising a component varying as a sinusoidal function of the

sum of said two angles and a component varying proportionally to said oscillations, and eliminating said second component by superimposing on said resulting quantity opposing quantities derived from said oscillations.
